[57] **CLAIM**

The ornamental design for a shoulder tote bag, substantially as shown and described.

DESCRIPTION

FIG. 1 is a perspective view of a shoulder tote bag showing our new design;

FIG. 2 is a top plan view thereof;

FIG. 3 is a front elevational view thereof;

FIG. 4 is a rear elevational view thereof, an intermediate portion of the carrying strap being broken away and omitted for convenience of illustration;

FIG. 5 is a bottom plan view thereof;

FIG. 6 is a side elevational view thereof, as viewed from the right of FIG. 3; the opposite side being substantially a mirror image thereof; and

FIG. 7 is a perspective view of the shoulder tote bag showing our new design in an open condition.
